US0D1061985S

(12) **United States Design Patent** (10) **Patent No.:** **US D1,061,985 S**
(45) **Date of Patent:** **** Feb. 11, 2025**

(54) **SOLAR LIGHT**

(71) Applicant: **Dahuan Huang**, Shenzhen (CN)

(72) Inventor: **Dahuan Huang**, Shenzhen (CN)

(**) Term: **15 Years**

(21) Appl. No.: **29/957,168**

(22) Filed: **Aug. 12, 2024**

(51) **LOC (15) Cl.** **26-05**

(52) **U.S. Cl.**

USPC **D26/69**

(58) **Field of Classification Search**

USPC D26/1-5, 24-29, 32, 34-37, 38, 40, D26/42-44, 46, 47, 49, 51, 52, 54, 57, D26/60-63, 65, 67, 68, 69, 70, 72, 73, D26/75, 76, 78, 80-84, 86-94, 97-99, D26/104, 106, 107, 109, 110, 111, 118, D26/124, 125, 126, 128, 138, 139, 140, D26/143; D21/578, 601, 606, 608, 615, D21/637, 451, 623, 483, 452, 531, 514; D10/106.8, 106.1, 104.1, 6, 23, 7, 15, 22, D10/12, 114.1, 2, 5; D16/203, 221, 202; D20/10, 29; D6/405; D25/100, 25; D14/171, 216, 214; D11/121, 125, 128, D11/163

CLAIM

The ornamental design for a solar light as shown and described.

DESCRIPTION

FIG. 1 is a perspective view of a solar light showing my new design;

FIG. 2 is another perspective view thereof;

FIG. 3 is a front view thereof;

FIG. 4 is a rear view thereof;

FIG. 5 is a left side view thereof; and,

FIG. 6 is a right side view thereof.

(Continued)

The dash-dash broken lines in the drawings depict portions of the solar light that form no part of the claimed design.

1 Claim, 6 Drawing Sheets
